UNITED STATES PATENT OFFICE.

HARRY O. DAVIS, OF IPSWICH, MASSACHUSETTS, ASSIGNOR TO SPRAY ENGINEERING COMPANY, OF BOSTON, MASSACHUSETTS, A CORPORATION OF MASSACHUSETTS.

MEANS FOR AND METHOD OF APPLYING COATING.

1,311,760.

Specification of Letters Patent.

Patented July 29, 1919.

Application filed December 30, 1918. Serial No. 268,919.

To all whom it may concern:

Be it known that I, HARRY O. DAVIS, a citizen of the United States, and a resident of Ipswich, in the county of Essex and State 5 of Massachusetts, have invented an Improvement in Means for and Methods of Applying Coating, of which the following description, in connection with the accompanying drawings, is a specification, like characters 10 on the drawings representing like parts.

This invention relates to means for and methods of applying coating to surfaces. The coating, if a liquid, may be a paint, 15 japan, varnish or other suitable coating means, or it may be a solid in powdered form, and the material to which it is to be applied may be of any suitable character, such, for example, as wood or metal.

One important object of my invention is 20 to provide an industrial tool which may be readily used in rough work not requiring a great nicety of manufacture nor costly and delicate parts. Obviously, however, the invention is adapted to fine work.

25 Referring more particularly to the drawing wherein I have represented a single embodiment of my invention and one form of means for practising my method, —

Figure 1 is a plan view of a tool constructed in accordance with my invention where- 30 by my method may be practised;

Fig. 2 is a side elevation thereof;

Fig. 3 is a vertical, central, sectional view thereof;

35 Figs. 4 and 5 are transverse sections upon the lines 4, 5 of Fig. 3 looking to the left in said figure; and

Fig. 6 is a view similar to Fig. 3 but representing the parts as differently positioned.

40 The tool or appliance by which preferably I practise my invention may be of any suitable material, but preferably it is metallic. The body 1 thereof may be of any suitable form and preferably is provided 45 with a handle or extension 2 integral therewith and having a passage 3 for the coating material, such, for example, as paint, and a passage 4 for the propelling agent, which preferably is a fluid under pressure, such, 50 for example, as air.

The coating material and the motive fluid under pressure may be received from any suitable source of supply, it being desirable that in this embodiment of the invention the

coating material shall itself be supplied under pressure. 55

In the disclosed form of my invention, the tool is of a general pistol form having an elongated handle or body portion 1, but the construction may be widely varied within 60 the scope and purpose of the invention.

If desired, I may provide a valve for the paint or other coating supply passage 3, but preferably I do not employ such a valve, but control the passage of the coating material wholly through the admission of the air or other motive fluid. Therefore, I extend the coating passage 3 to substantially the forward end of the tool to which I apply a cap 5 internally threaded as indicated at 65 and received upon the threaded end 7 of the tool. Preferably I provide the cap 5 with a removable lining or member 8 of suitable material, such as steel, which may be replaced when worn. The lining or member 70 8 thus constitutes a part of the cap. As shown most clearly in Figs. 3 and 4, the cap 5 or the removable lining 8 thereof is provided with an inner annular cavity 9 and an outer similar cavity 10, which are in communication by means of a plurality of substantially radial passages 11 herein shown as slightly forwardly inclined. 75

80 Preferably the coating material which is supplied through the passage 3 (herein shown as lined) is forced under pressure into the outer annular passage 10 from which it is forced under pressure into the inner annular passage 9, the pressure upon the coating material being in this embodiment of my invention equal at least to the pressure of the compressed air. 85

90 The compressed air passage 4 (also herein shown as lined) leads into the head of the tool and preferably into a valve chamber 12 having a prolongation 13 extending to the cap 5 so as to admit the motive fluid to the cap from which it is expelled through the valve controlled opening 14. 95

100 While any suitable valve means may be employed, I have herein represented a spindle 15 which is guided at or near its forward end in any suitable manner as by means of spaced lugs 16 formed upon the spindle. The tip end of the spindle is preferably tapered as indicated at 17, and the paint or other coating material is received upon the tapered or tip end of the spindle in a thin 105

layer to be discharged therefrom by the air or other motive fluid under pressure.

The spindle 15 is provided with a piston-like member 18. For that purpose I have represented the rear end of the spindle as threaded at 19, and as receiving a plurality of disks 20, 21, the disks 20 being preferably metallic washers and the disks 21 being preferably leather or like material compressed between the disks 20 and held in position by a nut 22. The rear end of the spindle 18 has a cross groove 23 for the reception of a screw driver.

The rear end of the chamber 12 is internally threaded as represented at 24 for the reception of a threaded nut 25 closing the piston chamber, and interposed between the piston 18 and the nut 25 is a coiled spring 26, one end of which is herein shown as received within an annular groove 27 in the inner face of the nut 25.

Preferably I provide an axial screw 28 having a knurled adjusting head 29, and I provide a lock nut 30. By adjusting the screw 28, I limit the extent of movement of the spindle 15 under the influence of the compressed air supply. The screw 28 also serves as a lock wholly to prevent the operation of the apparatus, this being effected by rotating the screw until its inner end contacts with the inner end of the spindle 15 when the latter is in the position shown in Fig. 3.

In accordance with my invention, I provide means whereby the air or other motive fluid may be supplied to one or both sides of the piston 18 according as it is desired to discharge the coating material or to prevent its discharge. For this purpose I have herein represented a valve chamber 31 which communicates by means of a passage 32 with the main air supply passage 4 and by means of a passage 33 with the valve chamber 12 between the piston 18 and the nut 25. Within the valve chamber 31, I position a ball or other suitable valve 34. The valve chamber 31 is tapped as indicated at 35 for the reception of a screw plug 36 having a beveled inner face 37 for the reception of the ball valve 34. The screw plug 35 is provided with an axial passage 38 within which is slidably received a spindle 39.

The spindle 39 is controlled in any suitable manner and preferably by means under the control of the hand of the user of the apparatus. For this purpose, I have herein represented the body 1 as having the handle portion 2 to which is pivoted at 40 a lever 41 which may be engaged by the palm of the hand, so as to press it inward against the outer end of the spindle 39. When the pressure of the palm is relaxed, the lever 41 is moved outward in any suitable way, as by means of the coiled spring 42 held in position upon a pin 43 tapped into the handle 2 of the tool.

When the parts are in the position shown in Fig. 3 the compressed air or other motive fluid is admitted to both faces of the piston 18, but since there is a larger effective exposed area at the right hand face of the piston 18, viewing Fig. 3, the spindle valve is forced forward, thereby cutting off the discharge of the paint or other coating material.

When pressure is applied to the lever 41, 75 the parts assume the position shown in Fig. 6, the air moving the piston valve into the position shown in Fig. 6, thereby permitting the air to sweep forward along the tapered end of the spindle valve 15 and to 80 discharge the thin layer of coating material through the opening 14 toward the surface to be coated or otherwise treated.

The spring 26 acts to force the spindle 15 and its piston 18 forward or toward the 85 left, viewing Fig. 3, when the supply of air is cut off, thereby closing the opening 14 and preventing the discharge of the coating material when the air supply is cut off.

The coating material supplied to the 90 tapered end of the spindle valve 15 is discharged therefrom by the compressed air and in such discharge is broken into very minute particles. The fineness of the division of the coating material depends upon 95 the velocity of the air or other motive fluid that is supplied through the passage 4.

Having thus described one illustrative embodiment of my invention, I desire it to be understood that although specific terms 100 are employed, they are used in a generic and descriptive sense and not for purposes of limitation, the scope of the invention being set forth in the following claims.

Claims:

1. Means for applying coating comprising a body member having passages for coating material and for a motive fluid under pressure, and valve means controlling the flow of motive fluid, and thereby to actuate a 110 valve positively to control the flow of the coating material.

2. Means for applying coating comprising a body member having passages for coating material and for a motive fluid under pressure, a valve controlling the flow of the said motive fluid, and means for controlling said valve through the agency of the said motive fluid. 115

3. Means for applying coating comprising a body member having passages for the coating material and for the motive fluid, a piston valve controlling the flow of the coating material and the motive fluid, and means whereby the piston valve is controlled 125 by the flow of the motive fluid.

4. Means for applying coating comprising a body member having passages for the coating material and for a motive fluid under pressure, a spindle valve having a tip por- 130

- tion to receive a layer of the coating material, and means controlled by the flow of the motive material to govern the position of said piston valve and to effect the discharge 5 of the coating material from the tip thereof.
5. Means for applying coating comprising a body member having passages for the coating material and the motive fluid, a piston valve controlling the discharge of the coating material and the motive fluid, and valve controlled means for admitting the motive fluid to either face of the piston, thereby to control the position of the piston valve.
6. Means for applying coating comprising 15 a body 1 having passages 3, 4, and a valve 15 having a piston 18 and valve controlled means for supplying motive material to either face of the piston.
7. Means for applying coating comprising 20 a body member having passages for the flow of coating material and for the motive fluid under pressure, a spindle valve adapted to be operated by the motive fluid and a manually controlled valve for governing the spindle valve by means of the flow of the motive fluid to said valve.
8. Means for applying coating comprising a body member 1 having passages 3, 4, a spindle 15 having a piston 18, a passage 30 33 for admitting motive material to the rear face of the piston and a valve 34 for controlling the passage 33.
9. Means for applying coating comprising a body member having passages for the 35 coating material and the motive fluid under pressure, a valve controlling the flow of both the motive fluid and the coating material, and means structurally distinct from said valve to lock said valve in closed position.
10. Means for applying coating material comprising a body member 1 having passages for coating material and for motive fluid under pressure, a valve governing the 45 discharge of the coating material and the motive fluid, and a removable cap 5 having therein an inner and a substantially annular outer concentric recess with connecting passages for the discharge of the coating material and the motive fluid.
11. Means for applying coating comprising a body member 1 having passages for the coating material and the motive fluid under pressure, a valve 15, a removable cap piece 5, and a lining member 8 having inner 55 passages for the coating material and the motive fluid.
12. Means for applying coating comprising a body member 1 having passages 3, 4 for the coating material and the motive fluid, a piston valve 15 having a piston 18, a spring 26, and means for admitting motive fluid to either face of the piston.
13. Means for applying coating comprising 60 a body member 1 having passages 3, 4 for the coating material and the motive fluid, a piston valve 15 having a piston 18, a spring 26, and means for admitting motive fluid to either face of the piston.
14. That method of applying coating to surfaces comprising forming a thin coating of the coating material upon a preliminary surface at a point in proximity to the point of final discharge of said coating material, 70 and where such discharge is controlled through air pressure and forcing air under pressure along the said preliminary surface so as to force the coating material therefrom, and to discharge it in a finely divided state against the surface to be coated.
15. That method of applying coating to surfaces comprising forming a thin coating of the coating material upon a preliminary surface at a point in proximity to a restricted outlet and supplying air under pressure longitudinally of and along said preliminary surface, so as to discharge the material from said preliminary surface through said restricted outlet in a finely divided condition and controlling, at the point of ultimate discharge, through air pressure, the flow of the coating material.
16. Means for applying coating comprising a body member having passages for 95 coating material and for a motive fluid under pressure, a valve at substantially the point of ultimate discharge, and means whereby the flow of one of said agencies operates said valve.
17. Means for applying coating comprising a body member having passages for coating material and for a motive fluid under pressure, a valve at the point of ultimate discharge, and means whereby the flow 100 of motive fluid under pressure operates said valve.
18. Means for applying coating comprising a body member having passages for coating material and for a motive fluid, a 110 valve at substantially the point of ultimate discharge, and means whereby the flow of one of said agencies operates said valve.
19. Means for applying coating comprising a body member having passages for 115 coating material and for a motive fluid under pressure, and a valve at substantially the point of ultimate discharge, and there governing the discharge both of the coating material and the motive fluid and controlled by the flow of one of said agencies.
20. Means for applying coating comprising a body member having passages for coating material and for a motive fluid under pressure, and manually controlled 125 means whereby the flow of the coating material is cut off at the point of ultimate discharge through the flow of one of said agencies.
21. Means for applying coating comprising 130

1. Means for applying coating comprising a body member having passages for coating material and for a motive fluid under pressure, and means whereby flow of the motive material is utilized to cut off the flow of the coating material at the point of ultimate discharge.
2. Means for applying coating comprising a body member having passages for coating material and for a motive fluid under pressure, said body member having a relatively large, annular chamber adjacent the point of ultimate discharge, for the coating material, a spindle valve extending through said chamber, and means including a motive fluid operated valve to control a stream of motive fluid along said spindle valve, so as to traverse said chamber and discharge the coating material therefrom in a finely divided condition.

23. Means for applying coating comprising a body member having passages for coating material and for a motive fluid under pressure, means to supply coating material, means to supply motive fluid under pressure, and valve means for the coating material acted upon by the pressure of the motive fluid, to change the effective position of the valve means.

24. Means for applying coating comprising a body member having passages for coating material and for a motive fluid and means whereby the flow of one of said agencies is utilized to cut off the flow of the coating material at the point of ultimate discharge.

In testimony whereof, I have signed my name to this specification.

HARRY O. DAVIS.
